ATTORNEY.

UNITED STATES PATENT OFFICE.

HENRY JAMES LEE, OF BIRMINGHAM, ENGLAND.

LOCK MECHANISM.

Application filed June 6, 1921. Serial No. 475,430.

To all whom it may concern:

Be it known that I, HENRY JAMES LEE, a subject of the King of Great Britain, residing at 174 Corporation Street, Birmingham, England, engineer, have invented a new and useful Improvement in Lock Mechanism, and do hereby declare the following to be a full, clear, and exact description of the same.

10 This invention has reference to an improved lock mechanism and is especially applicable for use in connection with the locking of automobiles against unauthorized use or theft, but its application is not limited 15 thereto.

The object of the present invention is the improved construction of the lock mechanism so as to reduce the number of parts and consequently reduce the cost of production, 20 while at the same time forming a secure locking means of the character referred to.

The invention consists of a lock comprising an outer casing containing a fixed section and one or more rotary members adapted 25 to be normally interlocked with the fixed section, the rotary member or members being formed with an eccentric section which upon rotation projects through or beyond a slot or slots in the casing and moves into 30 locking or locating engagement with corresponding recesses formed in the body which contains the lock.

The present invention will now be described with particular reference to the accompanying sheet of drawings in which like reference numerals indicate like parts in the different views:-

Fig. 1 is a longitudinal part sectional elevation through one construction of the lock.

40 Fig. 2 is a cross sectional elevation taken on line 2—2 of Fig. 1.

Fig. 3 is a part sectional longitudinal elevation showing an application of the lock as seen in Figs. 1 and 2.

45 Fig. 4 is a part sectional elevation of another application of the lock, the lock casing being slightly modified, and

Fig. 5 is an elevation taken at right angles to Fig. 4 as viewed from the right hand side.

50 Referring first to Figs. 1 and 2, the lock consists of a cylindrical casing 6 which is formed with a segmental slot 7 therein. Within the casing is located a fixed cylindrical section 8 and an abutting section 9 which is formed with an integral eccentric section

10, the section 9 being also formed with an integral cylindrical extension 11 which passes through and is located within the fixed section 8. The section 9 is capable of rotation by the use of a key. It is normally 60 interlocked with the fixed section 8 by means of the aligned plungers 12 which are controlled by the coil springs 13 located within the slots 14 in the fixed section 8, the fixed section 8 is locked to the casing 6 by means 65 of a pin 15 as seen in Fig. 1. When the key is inserted in the lock casing through the cylindrical aperture 6^a therein the section 9 formed with the eccentric 10 is freed from the fixed section 8 and can be rotated so that 70 a portion of the eccentric 10 projects through and beyond the segmental slots 7 in the lock casing 6. In Figs. 1 and 2 of the drawings the eccentric 10 is shown in the projecting or locking or locating position, and it will 75 be quite clear that a partial rotation of this section will withdraw it within the periphery of the lock casing 6.

Referring now more particularly to Figs. 1, 2 and 3, Fig. 3 shows one application of 80 the lock as seen in Figs. 1 and 2, normally the lock may be said to be mounted within the fixed member 16 which is formed with a locating slot 16^a therein to receive the eccentric section 10 when in the locking or locating position. In alignment with the apertured member 16 is an apertured member 17 which is normally adapted for a reciprocal motion. This member is formed with a locating slot 17^a therein which corresponds to the slot 16^a in the member 16 and when it is desired to fix the position of the member 17 relative to the member 16 the eccentric section 10 is withdrawn within the lock casing 6 and the lock bodily moved 95 forward to the position indicated by dotted lines in Fig. 3, when the eccentric section 10 is turned so that the projecting part thereof engages within the locating slot 17^a, by this means the member 17 is held against motion 100 and fixed in a determined position relative to the member 16.

Referring now to the modification and application seen in Figs. 4 and 5, the lock is mounted within the fixed bracket 18 which 105 is provided with two locating slots 18^a and 18^b. Mounted on a spindle 19 which is mounted in the bracket 18 is a lever 20 which is adapted to be reciprocated as indicated in Fig. 5 of the drawings. The 110

lock casing 6 in this construction is formed with a substantially rectangular extension 21 which is adapted to project into and be located within a similarly shaped slot 22 in the lever 20. When it is desired to lock the lever 20 in position relative to the bracket 18 the lock is bodily advanced as seen in Fig. 4 of the drawings until the extension 21 is located within the slot 22 of the lever. When in this position the eccentric section 10 of the lock is turned to engage within the locating recess 18^b formed in the bracket 18. When it is desired to free the lever 20 the eccentric section 10 is withdrawn within the lock casing and the lock bodily moved toward the left until the eccentric section 10 is coincident with the locating slot 18^a when the eccentric section 10 is again projected beyond the lock casing, this time into the locating recess 18^a, the extension 21 is now clear of the slot 22 in the lever 20.

The key can retract the casing 6 or the bolt 21 by frictional side pressure, or by forming the key stem with a lateral projection adapted to engage a bayonet slot 6^a in the retractable member.

The casing 6 is slidably mounted within the cylindrical socket of the member 16, or in the cylindrical socket of the bracket 18, and the casing is held against rotation by means of a feather 23 formed on the lock casing 6 and a key-way 24 formed in the member 16 or bracket 18.

From the foregoing description it will be seen that this improved lock mechanism may be permanently but adjustably secured in the body by which it is carried in which case the eccentric section could form the interlocking means between the free and fixed members, or alternatively the locking mechanism could be separable from the body in such a manner that the eccentric section forms the locating means the lock casing itself or a member secured thereto form the interlocking means.

Claims:—

1. A lock comprising in combination a

body which contains the lock, a casing having a segmental slot, a fixed section, a rotary section, spring controlled plungers co-axial with the longitudinal axis of the lock and adapted to interlock the rotary section to the fixed section, and an eccentric section carried by the rotary section which upon rotation projects through the segmental slot in the lock casing and moves into locking or locating engagement with corresponding recesses formed in the body which contains the lock. 50

2. A lock adapted for longitudinal movement so that the body of the lock can engage two or more members which are to be locked together said members having slots for engagement by the locking member of the lock, comprising in combination a casing having a segmental slot, a fixed section, a rotary section, spring controlled plungers co-axial with the longitudinal axis of the lock and adapted to interlock the rotary section to the fixed section, and an eccentric section carried by the rotary section which upon rotation projects through the segmental slot in the lock casing and moves into locking or locating engagement with corresponding recesses formed in the body which contains the lock. 65

3. A lock comprising in combination a body which contains the lock, a casing having a segmental slot and an end projection adapted to engage a member which has its path of motion at right angles to the longitudinal axis of said casing, a fixed section, a rotary section, spring controlled plungers co-axial with the longitudinal axis of the lock and adapted to interlock the rotary section to the fixed section, and an eccentric section carried by the rotary section which upon rotation projects through the segmental slot in the lock casing and moves into locking or locating engagement with corresponding recesses formed in the body which contains the lock. 80

In testimony whereof, I have signed my name to this specification.

HENRY JAMES LEE.
